by *Charles O. Yuller*
His Attorney.

UNITED STATES PATENT OFFICE.

CHARLES F. SCHWENNKER, OF SCHENECTADY, NEW YORK, ASSIGNOR TO GENERAL ELECTRIC COMPANY, A CORPORATION OF NEW YORK.

ELECTRIC SWITCH-OPERATING MECHANISM.

Application filed July 19, 1928. Serial No. 294,001.

My invention relates to mechanism for operating electric switches, and particularly to mechanism for operating switches at high speed such, for example, as is shown in the 5 Tritle Patent 1,560,440, November 3, 1925. It is an object of my invention to provide an improved switch operating mechanism of the character disclosed in the aforesaid patent in which a greater opening speed of the 10 switch is produced and in which the blow of the closing movement is cushioned.

My invention will be better understood from the following description taken in connection with the accompanying drawing, and 15 its scope will be pointed out in the appended claims.

Referring to the drawing, Figs. 1, 2 and 3 illustrate one embodiment of my invention respectively in open circuit position, in an 20 intermediate position and in closed circuit position.

I have chosen to illustrate my invention as applied to a liquid break switch having a pivotally mounted movable contact although 25 it should be understood that it is by no means limited to such a switch. The fixed contact 1 and the movable contact 2 are shown immersed in insulating liquid 3, such for example as oil, contained in the tank 4 having 30 the cover 5. The movable contact 2 is carried by the lever 6 which is fulcrumed at 7 and which is operated by the link 8. Floating lever 9 is pivoted at one end to link 8 and at the other end to the arm 10 at the 35 point 11. Arm 10 is secured to a shaft journalled in an auxiliary housing secured to the cover, a suitable opening being provided in the cover through which the arm projects. Rod 12 which is adapted to connect with any 40 suitable operating mechanism, not shown, such for example as a solenoid connects by another arm on the shaft, outside of the chamber which communicates with the interior of the switch. Lever 9 at an intermediate point thereof connects through link 45 13 with the pivoted armature 14 of the electromagnetic releasable retaining means 15. This means preferably is of the type disclosed in the above mentioned Tritle Patent 50 although other suitable retaining means may be used if desired. For cushioning the armature when the same moves to release posi-

tion I have shown the buffer 16 which may comprise several layers of felt. The powerful switch opening spring 18 is shown attached at one end thereof to lever at the point of connection therewith of the link 13 and at the other end to the fixed point 19. Switch closing spring 20 is shown attached at one end to pivot pin 11 between lever 9 55 and arm 10 and at the other end to the fixed point 21. To control the movements of the floating lever 9 I connect with it the dash pot 22 which as shown in the drawing is double-acting and comprises the cylinder 23 60 having one or more openings 24 in its intermediate portion and the piston 25 arranged to slide past the openings so as to be checked at either end of its stroke. For convenience I attach the cylinder and piston of the dash 65 pot to the same members to which the closing spring 20 is attached, namely, the pivot pin 11 and the fixed pin 21. The dash pot thus is immersed in the insulating liquid of 70 the switch and requires no additional liquid-tight retainer.

To cushion and to limit the opening movement of the switch, I provide a buffer comprising the arm 28 having the fixed pivot 29 at one end and engaging the compression spring 30 at the other end suitably supported from a fixed part of the switch frame. Roller 31 mounted on the pivot connection between lever 9 and link 8 rolls 80 on the upper side of arm 28 during certain portions of the switch opening movement.

The operation of the apparatus embodying my invention is as follows: Considering the apparatus to be in the open circuit 90 position illustrated by Fig. 1, a pull on operating rod 12 rocks arm 10, lever 9 and armature 14 against the force of springs 20 and 18. Upon reaching the pole piece of the electromagnet 15 the armature is retained thereby, the parts then being in the position illustrated by Fig. 2. During this movement the piston of the dash pot has made one traverse of the cylinder 95 and in so doing first expelled the liquid therein through the holes formed in the wall of the cylinder and then passed the holes at which time it excited a damping effect upon the further movement of

the mechanism. When the mechanism is operated with considerable force, as for example by a solenoid, and the movement of the parts is not checked at the end of 5 the stroke, the rebound of the armature 14 is sufficient to disengage with the magnet. Upon reaching the position shown in Fig. 2 the actuating force is removed from rod 12 whence spring 20 rocks lever 9 and arm 10 to the position shown in Fig. 3, the center of lever 9 being retained in the raised position by the armature 14. In this movement of lever 9 the switch is closed and the dash pot piston again traverses the cylinder. 15 In so doing it again expels the liquid through the openings in the cylinder and in passing on beyond them exerts a strong damping effect upon any further movement of the parts. The dash pot thus effectively 20 cushions the blow or shock of the forceful engagement of the cooperating switch contacts which it has been found set up vibrations sufficient in certain cases, particularly where butt contacts such as shown are 25 used to cause the release of the retaining means.

Opening of the switch is produced by releasing the electromagnetic retaining means. This may, for example, be effected 30 in response to a predetermined overload on the circuit controlled by the switch in the manner explained in the aforesaid Tritle patent. In the present description therefore it will be sufficient merely to assume 35 that the armature is released in response to some predetermined current condition. The retaining means thus released, the floating lever 9, rod 8 and switch lever 6 are moved at high speed by the opening spring 18. 40 The switch in its complete form includes in addition blowout coils and other features not shown in the drawing since they form no part of the present invention. Such a switch is capable of interrupting a power 45 current of many thousand amperes within one half cycle of the occurrence of a predetermined overload or short circuit.

When the parts are in the position shown 50 in Fig. 3 the dash pot piston is not at the extreme lower end of the cylinder so that the floating lever upon being released is capable of movement under the influence of spring 18 either bodily downward or 55 totally about the pivot pin 11. It will be apparent from an inspection of the drawing that for the greatest opening speed of the movable switch contact the lever 9 should have the aforesaid pivotal movement. Now this pivotal movement is assured by the dash pot 22, for at the beginning of the opening stroke, see Fig. 3, the dash pot piston is already in the lower portion 60 of the cylinder, that is, it is past the openings 24. Any ordinary burning away 65 of the switch contacts in service is auto-

matically compensated by pivotal movement of lever 9 about its connection with link 13. The dash pot thus in the last named function governs the movement of the mechanism when the switch is released to cause 70 the contacts to separate at the highest speed possible. The opening movement of the switch lever and associated parts is cushioned by the roller engaging the buffer arm 28 and the armature 14 engaging the buffer 75 16.

I have chosen the particular embodiment described above as illustrative of my invention and it will be apparent that various modifications may be made without departing 80 from the spirit and scope of my invention which modifications I aim to cover by the appended claims.

What I claim as new and desire to secure by Letters Patent of the United States, is:— 85

1. Switch operating mechanism comprising a floating member having a connection at one portion thereof with a switch to be operated, operating means connected to the member at another portion thereof, releasable retaining means for said member, and a dash pot connected with the member at that portion thereof to which the operating means is connected whereby upon the release of the retaining means the switch is operated with 95 the maximum speed.

2. Switch operating mechanism comprising a floating lever, means connecting one end thereof with a switch to be operated, operating means connected to the lever at the other end thereof, a second operating means connected to the lever at an intermediate point thereof, releasable retaining means for the lever and a dash pot connected with the lever at said other end thereof. 100

3. Switch operating mechanism comprising a lever, a connection between one portion thereof and a switch to be operated, operating means connected to another portion thereof, releasable retaining means connected to an intermediate portion of the lever and means comprising a dash pot operatively connected to the lever for cushioning the closing movement of the switch and for controlling the movement of the lever when 110 the same is released by the releasable means.

4. Switch operating mechanism comprising a floating lever, a connection between one end thereof and a switch to be operated, operating means connected with the other end of the lever, a releasable retaining means connected with an intermediate portion of the lever, an operating spring also connected with an intermediate portion of the lever and a dash pot connected with said other 120 end of the lever whereby the closing movement of the switch is cushioned and in the opening movement of the switch the lever is caused to fulcrum about its said other end. 125

5. Switch operating mechanism comprising 130

ing a floating lever, a connection between one end thereof and a switch to be operated, an operating lever connected with the other end thereof, an electromagnetic releasable retaining means connected with the lever at an intermediate point thereof, a switch closing spring connected with the lever at said other

end thereof, a switch opening spring connected with the lever at an intermediate point thereof and a dash pot connected with the lever at said other end thereof.

In witness whereof, I have hereunto set my hand this 18th day of July, 1928.

CHARLES F. SCHWENNKER.
